Primary Examiner — Lauren R Calve*(74) Attorney, Agent, or Firm* — Stetina Brunda Garred and Brucker(57) **CLAIM**

The ornamental design for a footwear hanger, as shown and described.

DESCRIPTION

FIG. 1 is a front perspective view of a footwear hanger of the present invention showing our new design in use in a first operational configuration;

FIG. 2 is a top plan view thereof;

FIG. 3 is front elevational view thereof;

FIG. 4 is a left end view thereof;

FIG. 5 is a right end view thereof;

FIG. 6 is a rear elevational view thereof;

FIG. 7 is a bottom plan view thereof;

FIG. 8 is a front perspective view of the footwear hanger of the present invention showing our new design in use in a second operational configuration;

FIG. 9 is a top plan view thereof;

FIG. 10 is a front elevational view thereof;

FIG. 11 is a right end view thereof;

FIG. 12 is a left end view thereof;

FIG. 13 is a rear elevational view thereof; and,

FIG. 14 is a bottom plan view thereof.

The broken lines illustrate environmental structure and portions of the hanger that form no part of the claimed design.

1 Claim, 6 Drawing Sheets(56)
